UNITED STATES PATENT OFFICE.

ERASTUS G. OAKLEY, OF SOUTHPORT, CONNECTICUT, ASSIGNOR TO BRIDGEPORT
BRASS COMPANY, OF BRIDGEPORT, CONNECTICUT.

ELECTRIC-LIGHT SOCKET.

Application filed January 24, 1924. Serial No. 688,223.

This invention relates to electric light sockets, and more particularly to an improved connection between the members of the usual two part socket. The sockets of this connection in general use at this time consist of an upper dome-shaped portion or socket cap, and a lower cylindrical shell-like portion called the socket shell. When electric light fixtures are installed the lead wires are usually passed through an opening in the upper end of the cap and connected to the terminals on the porcelain base disposed within the lower cylindrical shell. Thereafter it is necessary to secure the shell and cap firmly together so that there will be no danger of accidental disconnection of the two parts, but it is very desirable that the connection be such that these parts may be readily disconnected when desired. As the light bulbs are usually provided with a screw base to fit into the sockets, it is necessary to connect the parts of the socket together so that they will withstand a rotary strain, and therefore it is not expedient to connect them by any means which require a relative rotary movement of the parts, but on the other hand, it is preferred to provide such a connection that the parts may be secured together merely by a longitudinal thrust. While some such connections have been made in the past their provision has rendered the sockets more or less expensive and the connections themselves have not always operated in a satisfactory manner, for if they were so arranged that the parts of the cap could be readily disconnected the connection was not always sufficiently secure when the socket was in use.

One object of my invention, therefore, is the provision of a new and improved connection between the cap and shell of an electric light socket.

Another object of the invention is the provision of a connection between the cap and shell of an electric light socket which may be economically made and which will secure the parts of the cap against rotary movement as well as against separation.

A still further object of the invention is the provision of the cap and shell of an electric light socket with interengaging securing means designed to be engaged by a longitudinal thrust such that no matching of the parts will be required, but on the other hand, the

cap may be secured upon the shell in practically any position rotarily. 55

To these and other ends the invention consists in the novel features and combinations of parts to be hereinafter described and claimed. 60

In the accompanying drawings:

Fig. 1 is a side elevational view of an electric light socket embodying my improvements. 65

Fig. 2 is an enlarged fragmentary side elevational view of the shell and cap of the socket before the parts are connected. 65

Fig. 3 is a bottom plan view of the cap on line 3—3 of Fig. 2. 70

Fig. 4 is a sectional view of the cap on line 4—4 of Fig. 3. 70

Fig. 5 is an enlarged side elevational view of the socket, some parts being shown in section on line 5—5 of Fig. 1. 75

Fig. 5^a is a sectional view of the socket on line 5^a—5^a of Fig. 1. 75

Fig. 6 is a sectional view on line 6—6 of Fig. 1. 80

Fig. 7 is a view similar to Fig. 3 but showing a modified form of cap. 80

Fig. 8 is a sectional view of the cap shown in Fig. 7 secured upon a shell. 80

Fig. 9 is a sectional view on line 9—9 of Fig. 8. 85

Fig. 10 is a bottom plan view of a further modified form of cap. 85

Fig. 11 is a fragmentary sectional view of the cap and shell secured together. 85

Fig. 12 is a sectional view on line 12—12 of Fig. 10. 90

Referring to Fig. 1 of the drawings, I have shown a dome shaped socket cap 10 provided with the usual hub 11 containing a threaded opening 12 through which a set-screw may be inserted to hold the socket in place. The lower edge of the cap is provided with a skirt or flange 13 shown more especially in Fig. 4, this flange being covered in the finished cap by a collar 14. 95

The shell of the socket is shown at 15 and may be formed with the usual shoulder 16 to support the porcelain base which is customarily a part of such sockets. The lower portion of the shell is usually provided with threads 17 to support a shade-holder or the like, while at the upper portion is arranged a slot or opening 18 through which projects the switch key 19. 100

In order to connect the shell to the cap I

prefer to arrange on these parts interengaging means which may be economically formed, and which will effectively hold the two parts of the socket together. For this purpose the shell is provided with an annular series of corrugations consisting of alternate troughs or grooves 20 and ridges 21 which may be rolled or pressed into the metal by suitable machinery, and which terminate at their upper ends in an annular shoulder 22. As shown more especially in Fig. 2, this shoulder faces downwardly so that it may engage a part upon the cap to prevent an upward movement of the latter.

The cap is provided with co-operating projections adapted to engage the corrugations and shoulder upon the shell so that the two parts will be locked against relative rotary movement, as well as relative longitudinal movement. These projections consist of narrow strips of metal 23 struck out from the metal of the cap at their central portions to form bridge-like members, and wedge shaped members 24 also punched or struck up out of the metal of the cap and presenting an upwardly facing shoulder at their upper ends to engage below the shoulder 22 of the shell. The bridge-like members 23 are adapted to enter the grooves 20 and being contacted with the adjacent ribs 21 prevent relative rotary movement of the parts.

After the projections in the cap have been formed, the collar 14 may be placed about the skirt 13 and its edges clamped over the opposite ends of the skirt to hold it in place.

The cap 10 may be positioned upon the shell by a longitudinal thrust, the wall of the shell being permitted to spring inwardly to a sufficient extent due to the slot 18 for the switch key to permit the projections on the cap to pass the shoulder 22. The wall of the shell then springs outwardly so that the members 23 engage between the ribs 21, and the members 24 engage below the annular groove 22 to prevent separation of the parts.

In Figs. 7, 8 and 9 of the drawings I have shown a modified form of connecting means wherein the shell 15^a is provided with a series of corrugations comprising the grooves 20^a and ridges 21^a and the annular shoulder 22^a, all as shown in connection with that form previously described. The cap 10^a is provided in this instance with a plurality of punched or struck-up projections 26 in the shape of bridge members which are punched out from the metal of the cap at their central portions only. As clearly shown in Figs. 8 and 9, these bridge members are so shaped that the upper beveled portions thereof will engage below the annular shoulder 22 to prevent longitudinal separation of the parts, as well as engage in the grooves 20^a to prevent a relative rotary movement of the parts of the cap. In this instance the socket is not intended to be used with a key switch, but

is provided with a narrow slot 27 to permit the shell wall to spring inwardly so that the cap may be positioned on the shell.

In Figs. 10, 11 and 12 of the drawings I have shown a further modification in which the socket cap 10^a is provided with projecting tongues 28 struck out laterally from the skirt or flange portion of the cap. These projections are shown substantially triangular in shape and project inwardly from the periphery of the cap substantially at right angles thereto. There is also provided a projection 24^a similar to the projection 24 shown in connection with the form of my invention illustrated in Figs. 1 to 6 of the drawings. In this instance, the shell of the socket is provided with an annular series of corrugations consisting of alternate grooves and ridges, as clearly shown in Fig. 11. These corrugations are similar to those formed on the shell shown in Figs. 2 and 5, except they may be smaller in width and at the upper end of the corrugated portion the shell is provided with a shoulder similar to the shoulder 22. The corrugations in this instance are usually formed smaller than in the other modifications, for the reason that they are designed to receive the tongues 28 to prevent any relative movement of the parts in a rotary direction, and as the width of these tongues is just equal to the thickness of the metal of which the cap is made, the grooves of the corrugations need only be of sufficient width to receive these tongues. The tongue 24^a struck out from the cap at its upper end, similar to the tongue 24 shown in Fig. 5, engages below the shoulder formed on the shell and prevents separation of the parts in a longitudinal direction. As in the other forms, the cap is provided with a collar 29 to cover the openings left by striking out the projections 24^a and 28, so as to give it a finished appearance.

It will be obvious that I have provided an effectual, secure locking connection between the cap and shell of a light socket, the parts of which may be engaged by a longitudinal thrust, and when engaged will prevent relative movement of the parts either in a longitudinal direction or rotarily. When it is desired to disconnect the parts, however, pressure may be exerted with the thumb upon the shell adjacent the slots 18 or 27 and a locking projection at this portion of the cap will be disengaged and permit the parts to be separated.

It will also be obvious that as the series of corrugations and also the shoulder are formed to extend annularly about one of the parts, (the shell in the form shown) the locking engagement may be effected in practically any position of the cap and shell and there will be obviated the necessity of bringing these parts into certain registering positions before they may be locked, as has been 130 125

the necessity in the case of prior two part sockets.

While I have shown, illustrated and described some preferred embodiments of my invention, it will be understood that it is not to be limited to the exact details shown, but is capable of modification and variation within the spirit of the invention and within the scope of the appended claims.

10 What I claim is:

1. An electric light socket comprising a shell and a cap therefor, the metal of said shell being displaced inwardly adjacent the upper end thereof to form thereabove an annular shoulder on its outer surface, and a series of corrugations below said shoulder, and said cap being provided with integrally formed projections engaging below said shoulder to secure the shell and cap together, and with means to engage said corrugations to prevent relative rotation of the parts.

2. An electric light socket comprising a shell and a cap therefor, said shell having its wall displaced inwardly adjacent the upper end thereof to provide a downwardly facing annular shoulder on its outer surface, said displaced portion of the shell being corrugated to provide alternate grooves and ridges, and the cap being adapted at its lower end to telescopically receive the shell and having projecting tongues to engage below said shoulder to prevent separation of the parts, and means to engage the corrugations of the shell to prevent relative rotation of the parts.

3. An electric light socket comprising a shell and a cap therefor, said shell having the wall thereof adjacent the upper end displaced inwardly and corrugated, said corrugations terminating in a downwardly facing shoulder on its outer surface, the outside diameter of which is substantially equal to that of the body of the shell, and said cap being adapted to receive the upper end of said shell tele-

scopically, and being provided with means to engage the shoulder to prevent separation of the parts, and means to engage the corrugations to prevent relative rotation of the parts.

4. An electric light socket comprising a shell and a cap therefor, said shell having its wall displaced inwardly adjacent the upper end thereof to provide a downwardly facing shoulder on its outer surface, said displaced portion of the shell being corrugated to provide grooves and ridges, the upper end of said shell being adapted to be received telescopically within the cap, and the cap being provided with means to engage below said shoulder to prevent separation of the parts and to engage the corrugations of the shell to prevent relative rotation of the parts.

5. An electric light socket comprising a shell and a cap therefor, said shell having its wall displaced inwardly adjacent the upper end thereof to provide a downwardly facing shoulder on its outer surface, said displaced portion of the shell being provided with longitudinally disposed grooves, and the cap being adapted at its lower end to telescopically receive the shell, and being provided with means to engage said shoulder and the sides of said grooves to prevent separation and relative rotation of the parts.

6. An electric light socket comprising a shell and a cap adapted to be telescopically assembled thereon, one of said elements having its wall displaced from its normal position to provide longitudinally disposed grooves terminating in an annular laterally projecting shoulder, and the other element having integrally formed means to engage said shoulder and said grooves to prevent separation and relative rotation of the parts.

In witness whereof, I have hereunto set my hand this 22nd day of January, 1924.

ERASTUS G. OAKLEY.
